UNITED STATES PATENT OFFICE

REINHARD B. BARTELS, OF MELROSE, MASSACHUSETTS

SHOE AND SHANK STIFFENER THEREFOR

Application filed March 11, 1929. Serial No. 345,952.

It is sometimes desirable to produce a distinctive shape in the sole of a shoe at the ball line, such, for example, as the "cottage" or "circular". Heretofore this has commonly been done by the use of a specially formed shoe shank stiffener by either one of two methods. In accordance with one of these methods a plain steel shank stiffener has been used molded to the shape which it is desired

10 to produce on the shoe sole. In accordance with the other method a relatively narrow steel shank stiffener has been provided with a full length cover, either attached or separate, and made of a rather soft fiber-board

15 molded to the shape which it is desired to produce.

When the first method is employed the weight of the wearer of the shoe falls on the outer portion of the shank stiffener which is apt to force the inner portion up against the foot causing pressure to be exerted against the sensitive bones at the forward part of the arch, to the great discomfort of the wearer. This is particularly liable to occur if the stiffener is not positioned precisely as it should be in the shoe. In use also it has been found that such a stiffener has a tendency to wear through the outer sole at the ball line and as soon as the metal appears the wearer assumes that the shoe is defective and returns it for credit. When the second method is employed the fiber cover must extend substantially the full length of the stiffener in order that it may be securely held in place and as it is very susceptible to moisture, it does not hold its shape well while in service. It is also bulky and causes the shank portion of the sole of the shoe to be relatively thick.

40 In accordance with the present invention, however, the shape at the ball line is produced by a relatively small tip member molded to the desired contour from a water-resistant highly resilient material such as hard vulcanized fiber which is easily secured as

by a rivet to the forward portion of any desired form of metal shank stiffener. This fiber may be cut and molded on a steel press as when metal is used, but it has more resilience than the molded metal so that it does not cause discomfort to the wearer, nor tend in the same degree to wear through the outer sole. Even should it wear through the outer sole and show it does not present a metallic appearance to the wearer so that he is not likely to think that the shoe is defective. This vulcanized fiber, however, is sufficiently firm to retain its molded configuration, although it is sufficiently yielding to cause no discomfort to the wearer of the shoe, and it is not adversely affected by moisture.

A further advantage of this construction resides in the fact that it can be used with any desired form of metallic stiffener, and is not as bulky as the combination of metal stiffener with the full length fiber cover. It is also possible to associate molded tips of any desired shape with the same form of metal stiffener so that any desired configuration at the ball line of the sole may be produced very readily.

For a more complete understanding of this invention reference may be had to the accompanying drawings in which

Figure 1 is a perspective view of a shank stiffener having a fiber tip suitable to produce the "cottage" effect.

Figures 2 and 3 are top and side views, respectively, of the tip alone.

Figure 4 is a view similar to Figure 2, but showing a pair of tips made lefts and rights.

Figures 5 and 6 are top and side views of a tip for the "circular" ball line.

Figure 7 is a section on line 7—7 of Figure 1.

Figure 8 is a side elevation partly in section of a shoe showing the shank stiffener of Figure 1 in position therein.

Referring to Figure 1, at 1 is shown a metallic shoe stiffener which may be of any

suitable type, but as shown comprises a double metallic strip curved to the desired longitudinal curvature of the shank portion of a shoe and provided adjacent to its ends with prongs 2 and 3 by which it may be secured to an inner sole. To the forward end of this shank stiffener is fixed the tip 5 which is made of material resistant to moisture, but highly resilient, such, for example, as vulcanized fiber of the type commonly known in the trade as "granite fiber." This material may be slightly tempered by treating it with hot water for a suitable period and then may be molded to the desired configuration by presses such as used for molding metal articles. It may also be cut by the usual metal cutting dies but cannot be successfully treated by devices usually used for molding and cutting the softer grades of fiberboard.

As shown in Figures 1, 2 and 3 this tip is molded to form three plane portions 7, 8 and 9 angularly related to each other to form the relatively sharp edges 10, 11 and 12 intersecting at 13. These sharp edges and the resultant point at 13 conform to what is known as the "cottage" effect at the ball line of the shoe. At 14 is shown a perforation through the tip to receive a rivet such as 15 by which the tip may be secured to the forward end of the stiffener 1. Where it is desired to make the tips rights and lefts they may be made as shown in Figure 4 in which the outer forward end portions of the tip are extended as shown at 20. Where a "circular" ball line is desired, the tip may be molded to form a rounded projection 25 in place of the point 13 as shown in Figures 1 to 4.

In Figure 8 is shown a shoe having an outer sole 30 and an inner sole 31. Between these two soles is positioned the stiffener 1 with its tip 5 located so that the point 13 is at the ball line of the foot and positioned laterally where the desired point 32 on the outer face of the outer sole is to be positioned as is shown in Figures 7 and 8. Laterally in opposite directions from the point 32, the face of the outer sole slopes upwardly as is shown at 33 and 34 on Figure 7. In this figure a single strip metal stiffener is shown. Where the round ball line is desired the "circular" tip as shown in Figures 5 and 6 will be used, but it will be positioned substantially in the same manner as the tip shown in Figure 8.

The same construction, of course, might be applied to a turn shoe, the stiffener 1 being applied in accordance with usual practice to the lower face of the usual shank piece instead of to the inner sole as in the case of welt and McKay shoes as is well known to those skilled in the art.

Having thus described certain embodiments of this invention, it should be evident that various changes and modifications might be made therein without departing

from its spirit or scope as defined by the appended claims. By the term "tip" as used in these claims, I mean a member which does not extend rearwardly for the full or the major portion of the length of the metal stiffener to which it is attached but which extends only so far back as to permit it to be secured to the metal stiffener and to conform to the shoe sole contour at the ball or break line of the sole.

I claim:

1. A device of the class described comprising a metallic shank stiffener terminating at its forward end short of the ball line of a shoe sole, and a tip of hard vulcanized fiber molded to the contour of the desired ball line of said sole and secured to the forward end of said stiffener.

2. A shoe comprising inner and outer soles, a metallic shoe shank stiffener positioned between said soles, and a tip of water-resistant hard vulcanized fiber molded to the desired contour of the ball line of the sole positioned between said soles at said ball line and at the forward end of said stiffener and serving to maintain the ball line contour of the shoe.

In testimony whereof I have affixed my signature:

REINHARD B. BARTELS.
